DEVICE FOR RE-FORMING METAL TILES

Charles J. Jensen and Maurice E. Lawyer, Washington, N. J., and Henry A. Simpson, Oviedo, Fla., assignors to Vikon Tile Corporation, Washington, N. J., a corporation of New Jersey

Application August 17, 1949, Serial No. 110,824

2 Claims. (Cl. 153—2)

1

This invention relates to metallic tiles with bevelled or chamfered edges and, in particular, to the provision of a new and improved device for reforming such tiles.

It is an object of this invention to provide such a device which is of simple construction, which is light in weight, and which is readily portable, which properties render it particularly advantageous for use at the location wherein tiles are applied to walls of such shapes and sizes as to require the re-sizing, re-shaping or re-forming of certain of the tiles to conform to the wall shape and size.

It is a further object of this invention to provide such a device incorporating means whereby the marginal bevels, chamfers or flanges of the metallic tiles are reproduced simultaneously with the cutting operation on the edges thereof which are formed by the cutting device in re-sizing and in re-shaping a rectangular tile, as manufactured, to fit a space which is non-rectangular, i. e., trapezoidal, triangular, etc.

It is a further object of this invention to provide such a device wherein such means comprises detachable forming blades cooperating with the cutting edge of a relatively movable cutting blade of the device to form the aforesaid bevels, chamfers or flanges at the edges thereof which are cut by the device, simultaneously with the cutting of the edges and wherein the device is provided with sets of forming blades and means for housing these detachable forming blades of appropriate varying lengths to accommodate tiles of corresponding varying widths.

It is a further object of this invention to provide such a device embodying a swinging, or pivoted cutting blade or knife having an arcuate cutting edge adapted in all positions during a cutting operation to present to the tiles being cut, a cutting surface of appropriate inclination for facilitating cutting of the tiles.

It is a further object of this invention to provide such a cutting blade embodying a handle adjustable to various positions for facilitating operation of the device and for reducing the length thereof when inoperative.

These and other objects and advantages of the invention will appear in the following description and the drawing, forming a part thereof, and will be pointed out in the following claims.

In the drawing:

Fig. 1 is an isometric view of a preferred form of the device, with the cutting blade cut away in the interest of clear disclosure;

Fig. 2 is a plan view of the device with the cut-

2

ting blade in the position assumed thereby at the end of a cutting operation;

Fig. 3 is a view, in side elevation, of the structure shown in Fig. 2;

Fig. 4 is a fragmentary section taken along the line 4—4 of Fig. 1, and illustrating the manner in which extra forming blades are housed in the device when not in use;

Fig. 5 is a section taken substantially along the line 5—5 of Fig. 5;

Fig. 6 is a similar section taken substantially along the line 6—6 of Fig. 2;

Fig. 7 is a plan view of a forming blade similar to that shown in Fig. 2 but of shorter length, to 15 accommodate tiles of lesser width;

Fig. 8 is a view similar to Fig. 7 but showing a forming blade adapted to accommodate a tile of lesser width than that for which the blade of Fig. 7 is adapted;

Fig. 9 is a view similar to Figs. 7 and 8 but showing a forming blade adapted to accommodate trim tiles which are cut only "on the square";

Fig. 10 is a fragmentary plan view similar to 25 Fig. 2 but showing the use of the forming blade of Fig. 9 to accomplish the reduction of the length of a trim tile wherein the cut is made "on the square";

Fig. 11 is a section taken substantially along the line 11—11 of Fig. 10 and illustrating the manner in which the original end bevel or flange of the trim tile is reproduced at the cut or re-formed edge thereof;

Fig. 12 is a view similar to Fig. 10 but showing, in dash lines, the relative position of a tile and the device in making a cut "on the square"; and also showing in full lines the position of the same tile in making a cut "on the bias" or at an angle;

Fig. 13 is a view similar to Fig. 12, but showing the use of the forming blade of Fig. 7 with a wider tile;

Fig. 14 is a view similar to Fig. 11, but showing a modification in the structure of the forming blade; and

Fig. 15 is a view similar to Fig. 14 but showing another modification of the structure wherein a facing plate is applied to the righthand edge of the base of the device for cooperation with the swinging cutting blade thereof.

As shown in Figs. 1—6, the base or frame of the device, which is preferably formed of cast aluminum or other suitable material, is generally designated 20. This base is provided with a pair of longitudinal side flanges 21 and 22 which par-

ticularly adapt the device for support on the knee, for instance, of an operator or for support on any flat surface. The central portion of the base is provided with a plurality of longitudinal recesses 23, 24, and 25 which are adapted detachably to receive and house extra forming blades, when not in use. Secured to the upper flat surface of the base 20 by means of screws 27 is the top plate 26 provided with a scale 28 for convenience of locating the tile to be re-sized, re-formed and/or re-shaped. The scale 28, may, for instance, be etched in the top plate 26.

As shown particularly in Figs. 1, 2, 5 and 6, the top plate 26 does not extend entirely to the righthand edge of the base 20 but terminates a predetermined distance therefrom in order to provide accommodation for the forming blade generally designated 30 in Figs. 1, 2, 5 and 6. This forming blade is adapted to accommodate tile of extreme width or dimensions as, for instance, a tile 6" x 6".

Pivoted secured to the base 20 by means of screw 40, nut 41 and friction washer 40^a, is the cutting blade 42 which is swingable about the screw 40 as an axis for cooperating with the forming blade 30 to cut a formed tile and simultaneously re-form the edge thereof with a chamfer, bevel, or flange corresponding with the chamfers, bevels or flanges on the other edges which were formed when the tile was manufactured.

The cutting blade 42, especially as shown in Fig. 3, is provided with an arcuate cutting edge 43 so located and of such extent that the cutting edge presented to the tile throughout the cutting operation is of appropriate angularity to secure the ultimate cutting efficiency. The blade 42 is operated by the handle 44 which is pivoted about the screw 45 extending through an aperture in the free end portion of the blade 42. Wing screw 46, passing through suitably located apertures 47 or 48 of the handle, makes it possible to secure the handle 44 to the blade 42 in two positions, a third position being obtainable by passing screw 45 through aperture 48, as shown in Fig. 3, in order to facilitate operation of the blade 42 by an operator irrespective of the support or position of the base 20 of the device.

As shown in Fig. 2, the base 20 is provided also at its upper end with recesses similar to recesses 23, 24 and 25 adapted detachably to support the forming blade 30^c and a wrench 49 for adjusting screw 56.

The elongated recesses adapted to support the forming blades shown in Figs. 2, 7, 8 and 9 and wrench 49 all comprise elongated slots under which are similar narrower slots 51 each housing a friction spring 52 which is secured by means of a screw 53 to the base 20 as shown in detail in Fig. 4.

As shown in Figs. 2 and 5, a groove 55 is provided adjacent the righthand edge of the base 20 which groove 55 facilitates the removal of the forming blades 30—30^c (Figs. 1-9) from the base 20 after the lock screw 56 is released to make possible the changing of the forming blades as desired.

The forming blade 30, as shown in Fig. 2, comprises an elongated plate member provided with an aperture 39 receiving the lock screw 56 by means of which the blades are detachably secured to the base 20. Threaded apertures provided at suitable locations in the base 20 receive the lock screw 56 in its various positions for securing the forming blades 30—30^c to the base. The forming blade 30 (Fig. 2), for instance, may be adapted

to handle a tile of 6" x 6". This forming blade 30 is provided at its outer or righthand edge with a step 31 of width approximating very closely the thickness of the metal from which the tile is formed. Adjacent and inwardly of the step 31, is a chamfer or bevel 37 which is complementary with the edge chamfers, flanges or bevels formed in the tile when originally manufactured in the factory. Extending from the ends of the chamfer or bevel 37 are the end bevels or chamfers 38 which are disposed at acute angles to the bevel or chamfer 37 as shown in Fig. 2. The "cut away" or swept back relationship provided by this acute angular relationship between the end chamfers and bevels 38 and the bevel or chamfer 37 permits angular cuts to be made with the forming blades 30, 30^a and 30^b as illustrated in Figs. 12, 13 and 14.

The forming blade 30, as shown in Fig. 2, is also provided with a pair of circular apertures 33 which are adapted to receive the triangular upper sections of the locating studs 20^a. The longest forming blade 30, as shown in Fig. 2, is also provided with three circular locating apertures 34, 35 and 36, which cooperate with similar triangular upper sections of lock screws or studs 20^b accurately to align the forming blade 30 with respect to the base 20 and cutting blade or knife 42.

The afore-described lock screw 56, with its co-operating screw threaded aperture or socket in the base 20, prevents endwise movement of the forming blade 30 with respect to the base 20 and its top plate 26.

The forming blades 30^a and 30^b of Figs. 7 and 8 are similar to the above described forming blade 30 of Figs. 1-3 except of lesser length, corresponding parts being numbered accordingly.

The forming blade 30^c however, in addition to having the apertures 34, 35 and 36 omitted because of its reduced length, has the end bevels or chamfers 38 disposed at right angles to the front bevel or chamfer 37, adjacent the step 31. This arrangement is made because the trim tile to be cut and re-formed by the use of this blade 30^c is relatively narrow and hence is cut "on-the-square."

The trim tile, of which a fragment is shown and designated 60 in Figs. 10 and 11, is stamped or press formed from metal sheeting of thickness corresponding with the width of the step 31. As manufactured, the trim tiles are rectangular and of desired length, being provided with marginal flanges 61 forming chamfered or bevelled edges. With the tile 60 in the position of Fig. 10, actuation of the knife or cutting blade 42 will sever the tile as shown in Fig. 11 while simultaneously forming a new flange or bevel 61^a corresponding with the original flange or bevel 61. The bevels or flanges 61 and 61^a are complementary with the bevel or chamfer 37 of the forming blade 30^c.

As shown in Figs. 12 and 13, when either forming blade 30^b or 30^a (or 30) are used, the swept back end bevels or chamfers 38 permit the tile to be cut at desired acute angles up to 45 degrees.

The tile being cut in Fig. 12 is designated 62 and is of substantially greater width than the trim tile 60 described above. It is shown in dash lines in position for a square cut, and in full lines in position for an angular cut. As will be understood from Figs. 10 and 11, regardless of the angle at which the cut is made, the flange or bevelled edge 63 will be reproduced (as 63^a) on the

cut or severed edge simultaneously with the cutting or severance (Figs. 14 and 15).

The rectangular tile shown in Fig. 13 is designated 64 and its flanges or bevelled edges are designated 65. This figure, when taken with Fig. 12 illustrates that the tile can be cut at acute angles up to 45 degrees in either direction because of the provision of the swept back bevels or chamfers at both ends of the forming blades 30, 30^a and 30^b.

Fig. 14 illustrates a variation of the structure of Fig. 12 wherein the forming blade 70, substituted for the forming blade 30^b, is thinner than the blade 30^b and its top surface lies flush with the top plate 26 of the base or frame 20. The forming blade 70 terminates inwardly of the righthand edge of the base whereby a step is formed between the righthand edges of the blade 70 and the base 20, outwardly of the bevel or chamfer 37 of the blade 70. This step corresponds, functionally, with the step 31 of the forming blades 30, 30^a, 30^b, and 30^c.

In the embodiment shown in Fig. 15, the step 31 is omitted from the forming blade 70^a which is of the same thickness as the forming blade 30^b (Fig. 12). However, a step 72 is provided at the under side of the righthand edge thereof, which step rests upon the upper edge surface of the facing plate 73 which is secured to the righthand edge of the base 20 by means of screws 74.

From the above description it will clearly appear that we have provided new and improved devices which re-form and/or re-shape metallic tiles having flanged, bevelled or chamfered edge portions by a single operation wherein edge flanges, chamfers or bevels are formed at or adjacent the new cut edge simultaneously with the cutting of the edge and whereby each edge of the re-shaped, re-sized or re-formed tile is similar.

It will further appear that these devices are readily portable, of simple and fool-proof construction, compact and extremely efficient in operation fulfilling a long existing need for means effecting the re-sizing, re-forming and/or re-shaping of marginally bevelled metallic tiles at the location of their application to buildings and other structures, with ease and convenience and with such efficiency and neatness that the re-formed and/or re-shaped tiles can be distinguished from the fully factory formed tiles only with great difficulty and only by their shape or size.

It is, of course, to be understood that the above description is merely descriptive and nowise limiting, and that we desire to comprehend within our invention such modifications as are included within the scope of the appended claims.

Having thus fully described our invention what we claim as new and desire to secure by Letters Patent is:

1. In a device for re-shaping sheet metal tiles having flanged edges, a base having an elongated straight edge, a cutting blade pivoted to said base and having a cutting edge swingable in a substantially planar path past said straight edge of said base, and a forming blade detachably mounted

on said base for cooperation with said cutting blade, comprising an elongated plate member with a bevel spaced from one lateral edge a distance approximating the thickness of the tile forming sheet metal by a step of appropriate depth, said bevel being complementary with the original edge flanges of said tiles and parallel with the straight edge of said base, and a pair of end bevels similar to the aforesaid bevel leading from the ends of said first named bevel, said cutting blade when cutting a new edge simultaneously forming adjacent edge portions over said bevels to form edge flanges while progressively severing the sheet material forming said tiles.

2. In a device for re-shaping sheet metal tiles having flanged edges, a base having an elongated straight edge, a cutting blade having a cutting edge, movable in a substantially planar path past said straight edge of said base, and a forming blade secured on said base for cooperation with said cutting blade and comprising an elongated plate member with a bevel spaced from one lateral edge a distance approximating the thickness of the tile forming sheet metal, said bevel being complementary with the original edge flanges of said tiles and parallel with the straight edge of said base, and a pair of end bevels similar to the aforesaid bevel leading from the ends of said first named bevel at acute angles, the acute angularity of said end bevels facilitating cutting and forming of flanged edges disposed at acute angles to at least one original tile edge, said cutting blade when cutting a new edge simultaneously forming adjacent edge portions over said first named bevel to form edge flanges while progressively severing the sheet material forming said tiles.
